(57) **CLAIM**

The ornamental design for a wear block element for a three-point hitch assembly, substantially as shown and described.

DESCRIPTION

FIG. 1 is a left perspective of a wear block element for a three-point hitch assembly;

FIG. 2 is a right perspective view thereof;

FIG. 3 is a back view thereof;

FIG. 4 is a front view thereof;

FIG. 5 is a left side view thereof;

FIG. 6 is a right side view thereof;

FIG. 7 is a bottom view thereof; and,

FIG. 8 is a top view.

The broken lines in the drawing depict portions of the wear block element for a three-point hitch assembly that form no part of the claimed design.

1 Claim, 4 Drawing Sheets
